UNITED STATES PATENT OFFICE.

LOUIS F. NORTIER, OF BROOKLYN, NEW YORK.

DETONATING DEVICE.

1,290,300.

Specification of Letters Patent.

Patented Jan. 7, 1919.

Application filed August 12, 1918. Serial No. 249,533.

To all whom it may concern:

Be it known that I, LOUIS F. NORTIER, a citizen of Belgium, and a resident of the borough of Brooklyn, in the county of Kings, 5 city and State of New York, have invented certain new and useful Improvements in Detonating Devices, of which the following is a specification.

This invention relates to detonating devices of minor order, and appertains more especially to improvements in that class of articles which are known under the names of cracker bon-bons and snapper favors.

It is familiarly known that the so-called favors and bon-bons above referred to are usually made up into small packages containing a gift, prize, or confection of some sort, surrounded by a casing of light cardboard, to which a fuse and an explosive are attached, the whole being wrapped in tissue paper folded so as to let the fuse protrude outward, either alone or with an additional strip of paper used for a counterpart. Both of the latter must be of the same width so that they will lie closely one upon the other within a tight fitting wrapper in order to produce a satisfactory detonating effect. The wrapping of the strips has to be carefully done by hand and is therefore necessarily expensive. A further defect is found in the means hitherto adopted for effecting the detonation of the explosive, which are generally inadequate for the purpose in view.

One of the objects of the present invention is to produce an improved device of the character described enabling the "favor" or other article to be exclusively held within the casing provided therefor, and the detonator to be carried by the latter on its outer surface.

Another object is the production of a device of the nature set forth furnished with a wedging means adapted to be passed through a relatively constricted channel, whereby the explosive or detonating substance shall be set off positively in an unfailing manner.

A further object is to provide a device 50 of the class mentioned capable of being positively anchored to a container for a favor or the like by the same means as are employed for maintaining the effective constituent parts of the device operatively together.

Still another object is the provision of a device of the type specified which shall be

simple in construction, composed of few parts that do not require tight fitting nor careful wrapping, and susceptible of being expeditiously assembled by low-priced and 60 comparatively inexperienced labor.

Other objects and advantages of the invention will become apparent as the specification proceeds.

With the aforesaid objects in view, the 65 invention consists of the novel combinations and arrangements of parts hereinafter described in their preferred embodiments, pointed out in the subjoined claims, and illustrated on the annexed drawing, where- 70 in like parts are designated by the same reference characters throughout the several views.

In the said drawing:

Fig. I is a top plan view showing one 75 form of the present invention, parts thereof being broken away;

Fig. II is a longitudinal section of the same form of the device, taken along a line running somewhat below the center; 80

Fig. III is a top plan view of a simplified form of the invention, of the same species as that represented in Fig. I;

Fig. IV is a longitudinal section of the latter form, taken in a plane similar to that 85 in Fig. II;

Fig. V is a top plan view illustrating another variant of the invention;

Fig. VI is a longitudinal section, also taken in a plane slightly below the center 90 of the preceding view;

Fig. VII is a transverse section on the line VII—VII of Fig. V, looking in the direction pointed out by the arrows;

Fig. VIII is a fragmentary side elevation 95 and longitudinal section of a further form of the invention;

Fig. IX is a cross-section on the line IX—IX of Fig. VIII, viewed in the direction indicated by the arrows; 100

Fig. X is a perspective view of a snapper bon-bon provided with a single detonating device; and

Fig. XI is a perspective view of a similar article furnished with a plurality of detonators. 105

In these views the reference numeral "1" denotes a relatively fixed member, which as viewed in Figs. I and II occupies the lowermost position. This member may have any 110 desirable form; for instance, it may constitute the side wall of a casing wherein is

deposited the "favor" usually dispensed at certain social functions.

At a slight distance above the said member 1, is placed an auxiliary or protective member 2, likewise relatively fixed, but of much smaller dimensions. The latter-named member is united with the principal member 1 by means of a staple 3. The legs of this staple are positioned wide apart, as indicated by dotted lines in Fig. I to provide a comparatively elongated and semi-yielding portion intermediate of the extremities thereof, which are clenched under the bottom member 1, and serve to hold the top member 2, thereover, as clearly represented in Fig. II.

Between the two said members 1 and 2, is a movable element 4, preferably disposed parallel therewith. As shown, the element 4 may be held upwardly in contact with the top member, and it is arranged to slide between the same and the bottom member when pulled outwardly with relation to a favor or its container.

25 An ignitable compound 5 is carried at the under side of the aforesaid movable element 4, the same projecting downwardly therefrom in close proximity to the surface of the bottom member previously mentioned. As 30 Fig. II shows, the compound 5 may be applied to the inner extremity of the element 4, and made to fill, or approximately so, a gap or vacant space intervening between the latter and the bottom member.

35 Across the upper face of the bottom member 1, and substantially in alignment with the staple 3, above described, is laid a detonating composition 6, which is caused to adhere to the said face of the member. It will be observed, by referring to Fig. II, that the composition 6 about fills the same space or gap as the before mentioned compound 5, and together the compound and composition co-act in maintaining the movable element 4 in substantial parallelism with the relatively fixed members 1 and 2, whether applied in thin layers or in thick strata in the manner illustrated.

An enlargement 7, which may be produced 50 in any appropriate manner, is formed on the upper face of the movable element 4, directly over the compound 5, applied to the opposite side. Due to its peculiar location, this enlargement is adapted to exert a wedging action against the under side of the top member 2, when drawn past the latter, and will thereby cause sufficient friction between the compound 5 and composition 6 to effect the contemplated detonation, as they are 55 forced one against the other. The relative positions of these elements, substances, or ingredients 5 and 6, it will be noted, may well be reversed, if desired. The intermediate portion of the staple 3 is made semi-yielding 60 in order that the enlargement 7 may pass

thereunder without risk of tearing or otherwise injuring the movable member.

The variant form of the invention exemplified in Figs. III and IV comprises the same combination and arrangement of parts 70 as appertain to the two preceding views, with the exception of the stationary member 2, which is omitted. The several parts of this variant form are therefore numbered similarly to those before described, with the 75 addition of the exponent letter "a." The top member aforesaid being absent, it will be perceived that the wedging action of the enlargement 7^a of the movable element 4^a is effected directly against the under side of the 80 middle portion of the staple 3^a. The detonation is produced upon impact of the compound 5^a and composition 6^a, respectively carried by the inner end of the element 4^a, at the under side thereof, and by the relatively fixed member 1^a, on the latter's surface.

In that other variant form of the invention represented by Figs. V, VI and VII, the staple 8^b is inverted, and the turned over 90 extremities thereof serve as a pair of guides for the movable element 4^b over the stationary member 1^b. The enlargement 7^b in this form of the invention is produced by folding over the inner end of the element 4^b. It is 95 forced against and between the said extremities of the staple, which are oppositely disposed and set closely adjoining each other, as illustrated. The friction occurring between the compound 5^b and composition 6^b 100 here again causes the detonation.

It will be understood that the said ignitable compound and the said detonating composition may be mixed together, instead of being separate as hereinbefore described, in 105 which event the one mixture is worked with a companion surface made up of some abrasive material, substituted for the missing part. A construction embodying this feature is illustrated in Figs. VIII and IX, 110 where an abrasive surface is incorporated with the under side of the staple 3^c. Such a surface is conveniently produced by corrugating the under side of the middle portion of the staple, as shown. The co-acting ignitable and detonating ingredients may in 115 that case be placed together in one mass or body, as at 7^c, by the side of the said abrasive surface, while the parts 5^c and 6^c will merely constitute enlargements of the movable element 4^c and stationary member 1^c, 120 respectively. Or else, both of the parts 5^c and 6^c may be detonators, and 7^c an igniter. Another disposition of these sundry parts, productive of identical results, is to have 5^c 125 and 7^c both composed of mixed ignitable and detonating substances, on their respective sides of the movable element 4^c, and to utilize the part 6^c on the stationary member 1^c as the operating wedge or enlargement. 130

Other possible combinations of the same parts will be readily discerned by experts in the art to which the present invention appertains.

5 Fig. X shows how the staple 3^d may be employed to hold the movable element 4^d in position on the stationary member 1^d, and also to fasten together the opposite ends, edges, or other lapping portions of this 10 member when rolled upon itself to form a casing for the favor, or the like. A relatively fixed element 40 is represented as projecting outwardly from a wrapper 10, enveloping the said casing as well as the movable element 4^d and other related parts as a 15 whole. The element 40 is secured in position on the side of the casing member 1^d by a wire staple 30, which also serves to fasten together the opposite parts of this casing at 20 the end remote from that where the staple 3^d is applied.

In Fig. XI is depicted another species of casing member 1^e, on which a plurality of 25 movable elements 4^e can be maintained under each of a series of staples 3^e, disposed peripherally around the external circumference of the said casing, at one end thereof. At the opposite end of the casing member 1^e 30 is shown a plurality of similar movable elements 4^e each independently held to the side of the member 1^e by its own staple 3^e. Both series of movable members 4^e and 4^e, it will be observed, are provided with their respective detonating enlargements 7^e and 7^e, 35 adapted to be set off upon being pulled outwardly under or against the corresponding staples 3^e and 3^e. With this arrangement, it is now obvious that by pulling out the said movable elements 4^e and 4^e one after another 40 at either end of the stationary member 1^e, a person or couple manipulating the same can produce a continuous volley of cracking sounds, well calculated to cause surprise and merriment.

45 Due to the width of space provided between the legs of the staple 3, Figs. I and II, the movable element 4 is allowed sufficient freedom of motion to enable it even to be pulled sidewise, and yet the ignitable composition 5 thereon will obtain the required contact and frictional impact with the detonating composition 6 upon the stationary member 1. The same observation applies to the other forms of the invention wherein the 55 movable member is arranged to pass through a wide staple.

In Figs. V, VI and VII, a seal 8, indicated by dot-and-dash lines, is shown as extending over the ignitable and detonating 60 constituents. This affords a protective covering, which prevents injury to these substances through exposure to the atmosphere. When thus protected by sealing matter, the device is especially suitable for use as a low-priced burglar alarm. For such use, the 65

member 1^b and element 4^b can be readily fastened, for instance by means of thumb-tacks, just one for each, to the edge of a door and its trim, or to the adjacent upper and lower stiles of a pair of window-sashes. 70

As shown in the lower half of Fig. XI, the staple 3^e may continuously encircle, or approximately so, the casing member 1^e. However, two or more such staples may be employed instead to secure the plural movable elements 4^e around the said member, if preferred. 75

The before described staple 3 may be of flattened cross-section as represented in the annexed drawing. But, in lieu thereof, an ordinary book-binder's stitch can be resorted to, if desired, to attach the igniter, as well as the detonator, on either the outside or the inside of the relatively fixed member 1. The shape of the latter is rather immaterial, as various forms thereof besides that shown may be used with equally satisfactory results. 80

The aforementioned detonator and igniter, to wit, the chemical ingredients possessing the physical properties of producing a distinctly audible sound or loud report and generating or setting off the same, may be inclosed, either individually or combined, in a cap of approved design, which in turn can 85 be glued or otherwise affixed to the movable element 4, or its equivalent. 90

A shield 9, of fireproof material, may be superimposed upon the inner end of the movable element 4^d, and the juxtaposed ingredients 5^d, 6^d and 7^d as represented in Fig. X. This will preclude ignition or combustion of the enveloping wrapper 10, which possibly might result from a spark, flash, or flare-up of the fulminate or detonating substance employed. 100

105 It should be noted that the invention is not confined to the precise forms and exact details of construction herein specified and illustrated in the various figures of the drawing hereto annexed, as obviously numerous changes, alterations, and modifications can be effected in the same, without departing from the fundamental principles of the invention or sacrificing any of its 110 chief advantages. The right, therefore, of making any or all such changes, alterations and modifications, is entirely reserved.

115 Having described my said invention, what I desire to secure by Letters Patent, and 120 claim is:—

125 1. A device of the character described including a relatively fixed member, an element movable in relation to the same, a retainer serving to hold said member and said element in operative position together, an igniter and a detonator respectively attached to the member and the element so as to be capable of coming into contact one with the other, and means adapted to cause 130

- an impact of said igniter with said detonator by passing through said retainer.
2. A device of the character described including a relatively fixed member, a detonator and an igniter adapted to be carried one past the other, an element movable so as to cause said detonator and said igniter to come together, a retainer holding said member and element in operative position, and means on the movable element serving to depress it within said retainer, thereby setting-off the contacting igniter and detonator.
3. A device of the character described including a plurality of relatively fixed members placed parallel to each other, an element movable therebetween, a retainer for the fixed members affording a guide for said element, an igniter and a detonator respectively held in opposed relation between the movable element and one of the fixed members, and means adapted to exert a wedging action against the other fixed member during passage of the element across the guide.
4. A device of the character described, including a relatively fixed member, an element movable thereover, a retainer operatively holding the latter with relation to the former, a detonator within said retainer, an igniter carried by said element in position to be rubbed against said igniter, and wedging means also on the movable element adapted when passed by the retainer to press the detonator and igniter together.
5. A device of the character described including a relatively fixed member, a staple attached thereto, an element movable through said staple, a detonator and an igniter respectively carried by said member and said element, and an enlargement provided on the movable element at the side thereof, opposite from said igniter and said detonator, whereby the latter are forced together upon being passed through the staple.
6. A device of the character described including a relatively fixed member, a staple thereon, having a comparatively elongated semi-flexible intermediate portion, an element movable through the latter, a detonator and an igniter respectively carried by said member and said element, and means also carried by the movable element exerting a wedging action against said staple while passing therethrough to cause the igniter to set off the detonator.
7. A device of the character described including a relatively fixed member, an element movable thereover, a staple operatively holding the latter to the former, a detonator and an igniter of substantially equal magnitude, facing the same intermediately of the fixed member and the movable element, and an enlargement also pertaining to the movable element situated opposite said igniter and said detonator, said enlargement being designed to pass through said staple.
8. A device of the character described including a relatively fixed member, a staple thereon having an abrasive surface, a movable element adapted for passage through said staple, and a combined igniter and detonator carried by said element in position to strike against said surface as it passes through the staple.
9. A device of the character described including a relatively fixed member and an element movable with relation thereto, a staple straddling said element, a detonator and an igniter respectively carried by the fixed member and the movable element in position to meet each other, a wedging means on the opposite side from said igniter and detonator designed to be acted upon by the staple, and a seal normally covering the detonator and igniter.
10. A device of the character described including a casing for a favor or similar article, said casing constituting a relatively fixed member, a retainer securing opposite portions of said casing to one another, an element movable through said retainer, a detonator adapted to be set off by said element, and means on the latter exerting a wedging action against the retainer during passage of the element therethrough.
11. A device of the character described including a casing for a favor or similar article, a staple secured exteriorly thereof, an element movable through said staple, a detonator, means on said element operating to exert a wedging action against the staple during its passage therethrough so as to set off said detonator, a shield over the latter and a wrapper enveloping said casing exteriorly of said shield.
12. A device of the character described including a casing for a favor or similar article, a plurality of elements movable longitudinally with relation to the same, means for operatively retaining said elements on said casing, detonators, and an enlargement on each element adapted to exert a wedging action against said retaining means during passage of the elements therethrough and thereby set off the detonators.
13. A device of the character described including a relatively fixed member, an element movable in relation to the same, a detonator and a wedging means respectively carried by said member and said element, and a staple taking over the movable element providing a constricted passage, whereby said wedging means is caused to set off said detonator.

LOUIS F. NORTIER.
